TOOL POST

Tacitus W. Gaillard, Baldwin, N. Y.

Application August 15, 1947, Serial No. 768,848

1 Claim. (Cl. 82—37)

1

This invention relates to new and useful improvements in means for adjusting tools in various positions in tool posts.

An object of the invention is to provide a simple, efficient, durable, and easily operated device whereby the position of a tool on a post may be readily varied over a wide range of longitudinal and angular positions.

A further object is to provide a construction whereby the tool adjustments may be made quickly and with a high degree of fineness and accuracy and without any special skill on the part of the operator.

Further and more specific objects, features, and advantages will more clearly appear from the detailed specification hereinafter set forth especially when taken in connection with the accompanying drawings which illustrate present preferred forms which the invention may assume and which form part of the specification.

In brief and general terms, the invention is related to a tool post of the usual type which generally has a vertical slot therein. Related to the slot and the post is a seat having a curved recess in which is seated the curved lower face of an adjustable shoe. On the top of the shoe rests a tool supporting bar, and on top of that a cam block or element which may be slid back and forth slightly on the bar. Manual means is provided to move the shoe on its curved seat to vary the slope of the upper face of it and thereby to adjust the slope of the tool shaft. After the proper slope is achieved the cam block is moved by manual means to press down on the bar and jam it in place.

More particularly the shoe is moved either by hand or by means of a threaded shaft connected to one end of the shoe and operated by a hand wheel to obtain fine adjustments. The cam block is moved by engagement with a pivoted arm fixed at one end to the post and resting in a notch in the block at the other end. A threaded shaft is connected to the block and the shaft is moved by turning a threaded hand wheel or by oscillating a hand lever adapted to engage the wheel to turn it.

The present preferred form which the invention may assume is illustrated in the drawings, of which,

Fig. 1 is an elevation of the tool post construction with certain portions broken away;

Fig. 2 is a plan view of the device;

Fig. 3 is a vertical section taken on the line 3—3 of Fig. 2;

Fig. 4 is a vertical section taken on the line 4—4 of Fig. 2; and,

2

Fig. 5 is a perspective view of a modified form of adjusting shoe.

Referring now merely to the specific forms of the invention illustrated herein, it is seen that the device comprises a slotted post 10 having an enlarged head 11 at its lower end and adapted to slide in a track 12 in the base member 13. Around the post 10 on top of the track 12 is a ring plate 14 having a flat lower surface and a concave upper surface in which is seated an adjusting shoe 15 having a curved lower surface resting in the concavity of the plate 14 and a flat upper surface on which rests a tool supporting bar 16.

On the outer end of the bar 16 are disposed well-known clamping elements 17 and 18 between which is clamped a tool 19. In order to clamp the bar 16 in position on the shoe 15 there is provided an arm 20 pivoted at the top of the post slot on a pin 21 and having its lower curved end 22 resting in a cavity or recess 23 on the upper surface of a cam block or element 24 which is adapted to be slid along the surface of the bar 16. An adjusting rod 25 is connected to the rear of cam block 24 and is threaded at 26 on its outer portion and is guided through a bore in a strap 27 slidably embracing the post 10. This bore is of sufficiently large diameter greater than that of the rod, as shown, to permit a certain ample amount of lateral axial movement of the rod with respect to the strap thus preventing binding as the shoe 15 may be angularly adjusted. A hand wheel 28 interiorly threaded is mounted on this portion of the rod 25 and as it is turned it tends to move the rod axially in one direction or the other and thus slide the cam block 24 along the top of the bar 16. This movement will either tighten or loosen the pressure between the block 24 and the bar so as to hold the shaft firmly in any adjusted position.

The hand wheel 28 has notches 29 around its periphery which are engaged by a pin 30 projecting laterally from a hand lever 31 which is at its lower end slotted at 32 to pass around a sleeve 33 fixed to strap 27. In the slot 32 beneath the sleeve 33 is a spring 34 to resist the axial movement of the lever 31 to lift the pin 30 out of a notch 29. It will be clear that the lever may be used to turn the hand wheel 28 instead of the hand of the operator. It will thus be clear that by turning the hand wheel 28 by hand or by the intermediary of the lever 31 the shaft 25 is longitudinally moved to slide the cam block 24 along the top of the tool bar 16 and press it against said bar due to the camming action of the pivoted arm 20. Therefore the tool bar may be easily,

quickly and firmly adjusted in any desired set position as to its length adjustment.

Now as to the angular adjustment of the tool bar 16, reference is had to shoe 15 which has a curved bottom resting in a similarly curved cavity or seat on the bottom of the tool post preferably the ring plate 14. It is clear that as the shoe is moved backward or forward, the slope of its upper face will be altered and will therefore alter the slope of anything resting on it which in this case is the tool bar 16. In order to so move the shoe in the simplest form of the device I provide a lug 35 on top of a laterally disposed block 36 connected to one end of the shoe as seen in Fig. 5. In this case the adjustment is simple and inexpensive. However, this adjustment is not so fine or accurate as might be desired under certain circumstances so the form of adjustment shown in Fig. 3 is available. This consists of an upright pin or ball-headed stud 37 projecting universally into the end of a casing 38 on the end of a threaded shaft 39. This shaft threadably engages a sleeve 40 which is rotatably mounted in a bore in a block 41 and the sleeve has a hand wheel 42 connected to one end thereof. By turning the wheel 42 the sleeve is turned and moves the shaft 39 axially and thus moves the casing 38 and with it the shoe so as to adjust the slope of the shoe on its curved seat. The block 41 is formed of two plates held together by screws 43 and one of these plates has a stud 44 projected into a bore in the side of the post 10 with an annular groove 45 therein to receive a short pin 46 which holds the stud in the bore but permits the slight rotation of the stud caused by the slight change in the angle of the shaft 39 as the shoe 15 is adjusted. Thereby the turning of the wheel 42 permits very fine adjustments of the shoe and therefore very fine adjustments of the tool bar 16. These various adjustments are easily and quickly achieved to a fine degree and permit wide variations in the position and angularity of the tool to be made.

In Fig. 4 is shown a simple construction whereby the device or parts thereof may be lubricated. The end of pin 21 extends through the post 10 and is hollowed out as at 47. Over the end of the shaft or pin 21 is tight-fitted a casing 48 having a chamber 49. An oil filler pipe 50 extends into the chamber 49 and through the hollow end 47 of the pin 21 and has a lateral passage 51 con-

necting to this hollow end 47. Thus when oil is introduced into the pipe 50, it will fill the chamber 49 and pass into the hollow end 47 of the pin 21 through passage 51 and will then seep around the bearing of the pin and permit it to pivot freely on the top of the post 10 and reduce the resistance to movement to a minimum.

While the invention has been described in detail and with respect to present preferred forms which the invention may assume, it is not to be limited to such details and forms since many changes and modifications may be made in the invention in its broadest aspects. Hence it is desired to cover any and all forms and modifications of the invention which may come within the language or scope of the appended claim.

I claim:

In a device of the class described, a post, a shoe associated therewith and having a lower curved surface, a seat on which the shoe rests and having a similarly curved surface, a stud on one end of the shoe, a threaded member loosely connected at one end to said stud, a block connected to the post and having a rotatable threaded sleeve through which said threaded member extends, and a wheel on the sleeve whereby turning the wheel will longitudinally move the threaded member to move the shoe longitudinally of its seat to alter the slope of the shoe.

TACITUS WM. GAILLARD.
